UNITED STATES PATENT OFFICE.

EDWIN H. JANES, OF CLEVELAND HEIGHTS, OHIO.

WHEEL.

1,309,095.

Specification of Letters Patent.

Patented July 8, 1919.

Application filed January 10, 1917. Serial No. 141,697.

To all whom it may concern:

Be it known that I, EDWIN H. JANES, a citizen of the United States, residing at Cleveland Heights, in the county of Cuyahoga and State of Ohio, have invented a certain new and useful Improvement in Wheels, of which the following is a full, clear, and exact description, reference being had to the accompanying drawings.

10 This invention relates to cast metal wheels which, while capable of employment with various types of tires—secured in place either by bolting or by being pressed on—is especially well adapted for use with dual 15 tires. The invention also contemplates the production of a wheel in a single casting which has certain novel characteristics whereby its efficiency is enhanced and its production as an intact casting may be accomplished, without resultant shrinkage cracks. Further and more generally stated, the invention may be defined as consisting of the combinations of parts embodied in the claims hereto annexed and illustrated in the drawings accompanying and forming part hereof, wherein Figure 1 represents a perspective view of such wheel; Fig. 2 an elevation of the wheel taken from the inner side thereof; Fig. 3 a vertical sectional view taken 20 through half of the wheel; Fig. 4 an elevation of the wheel taken from the outer side thereof; Fig. 5 a sectional view corresponding to the line 5—5 of Fig. 3 and looking in the direction of the arrows; and Fig. 6 a 25 sectional detail through one of the spokes corresponding to the line 6—6 of Fig. 3 and looking in the direction of the arrows.

As previously stated, the wheel forming the subject matter of this application is 30 primarily designed as a cast metal wheel wherein the hub, spokes, and felly are made as a single casting which is afterward properly machined for the purpose of finishing and adapting the same to cooperate with 35 other parts, such as the disk which forms an inner face of the hub flange and the rims on which the tires are seated.

The wheel disclosed specifically herein 40 comprises a hub having a tapered or frusto conical hub flange projecting therefrom, spokes extending from the said hub flange, and a double-walled felly the inner and outer walls whereof are connected by side walls, the inner and outer walls being connected by a central circumferential rib. For 45 the purpose of lightening the construction,

the outer wall is provided with openings on each side of the central rib, between the latter and the side walls, the pillars or braces which are left between the central portion 60 of the outer wall and the side portions thereof serving to prevent the collapse of the side walls through the application of a tire base under great frictional pressure to the outer wall.

65 Describing by reference characters the various parts illustrated herein, 1 denotes the hub proper of the wheel, which hub has a cylindrical interior, preferably with a pair of short annular flanges 2 there- 70 within. At its outer end the hub is shown as threaded—see 3—whereby it is adapted to receive a hub cap, if desired. 4 denotes a tapered, substantially frusto-conical flange, which extends radially outwardly 75 from the hub proper and toward the inner (or body-facing) side of the wheel and having its peripheral flanged portion 5 machined to fit and center the brake drum. Cast with this flange are the spokes 6, said 80 spokes being substantially U-shaped in cross section and having their flanges presented toward the inner side or face of the wheel, the flanges of the spokes merging with the hub flange 4. Radial ribs 7, which are 85 preferably staggered with respect to the spokes 6, are formed with the hub flange 5 and serve to connect the interior surface thereof with the hub proper 1, and each of these ribs has formed therewith an inter- 90 orily threaded boss 8 which is adapted to receive a correspondingly threaded bolt or other means for assisting to secure thereto a disk, such as one of the end walls of a brake drum.

95 At their outer ends the spokes 6 merge with and abut against the inner cylindrical wall 9 of the felly. This felly comprises not only the wall 9 but radially extending side walls 10 and a cylindrical outer wall, indicated generally at 11, said cylindrical outer wall being lightened by providing a series of openings 12 between the central portion of the wall and the sides thereof. The central part of the segmental outer wall is connected to the inner wall by means of a rib 13 which is cast with the inner and outer walls. The rib 13 is substantially T-shaped in cross section. Where the tires are to be bolted on, the walls 10 will be provided with 100 alined bolt-receiving apertures 14 and the rib 13 with correspondingly located in-

wardly extending recesses 15, the recesses being of sufficient depth and width to provide clearance for the bolts extending through the apertures 14 and connecting the 5 tires to the outer wall of the rim. It will be observed that the pillars or braces 16 on each side of the openings 12 and extending between the sides and the central portion of the outer rim wall transmit pressure from 10 either of the side walls 10 to the central portion of the outer cylindrical wall and thus prevent the collapse of such side walls in cases where great frictional resistance is encountered in pressing a tire base upon such 15 outer wall. Furthermore, in order to minimize the amount of machining performed upon the outer wall in order to form a proper seat for a tire base, the outer faces of the pillars or braces 16 will be depressed 20 slightly with respect to the central and lateral portions of the outer wall on which the tire base will be seated. Where a tire base is to be secured by means of bolts, the bolts will be applied to the apertures 14 and 25 will extend through the notches or recesses 15.

The cylindrical hub proper, the hub flange 5, the spokes 6, and the various parts of the felly are preferably made of the same thickness of metal, the parts being thereby prevented from cracking through the cooling of the casting. It has been found that, by so doing, the best results are obtained in casting the wheel.

After the casting operation, the ends of the hub, the flanges 2 and the inner face of the hub flange 5 with its associated parts will be machined; also the outer wall of the felly. While, in the drawings, the side 40 walls 10 of the felly and the central rib 13 are shown as provided with apertures for bolts, it will be evident that the outer wall is adapted to receive either the channel bases of pressed-on tires or the wedges used with 45 demountable tires. Furthermore, because of the structural features described herein, the wheel can be produced conveniently and economically from a single casting and without the production of cracks due to shrinkage.

The wheel shown, described and claimed herein is similar to that shown, described and claimed in my application No. 83,468, filed March 11, 1916, being as to the features 55 common to the two applications a continuation of such earlier application.

Having thus described my invention, what I claim is:—

1. A wheel comprising a hub, spokes, and 60 a cast double-walled felly the inner wall whereof is connected to said spokes, the inner and outer walls of the felly being connected and said outer wall comprising a centrally arranged tire supporting portion, and tire 65 supporting portions on each side of the first

mentioned portion, there being braces or pillars extending between the central portion and the side portions of such outer wall, the outer surfaces of said pillars or braces being depressed with reference to the central 70 and side portions of such outer wall whereby the tire base will be seated upon such portions but will not be seated upon such braces or pillars.

2. A wheel comprising a hub, spokes, and 75 a cast double-walled felly the inner wall whereof is connected to said spokes, the inner and outer walls of the felly being connected by side walls and said outer wall comprising a centrally arranged tire supporting portion, and tire supporting portions on each side of the first mentioned portion and connected to the side walls, respectively, there being braces or pillars extending 80 between the central portion and the side portions of such outer wall, and a circumferential rib extending between the central portion of the outer felly wall and connecting the same with the inner wall, the outer surfaces of said pillars or braces being depressed with reference to the central and side 85 portions of such outer wall whereby the tire base will be seated upon such portions but will not be seated upon such braces or pillars.

3. A wheel comprising a hub, spokes, and 90 a cast double-walled felly the inner wall whereof is connected to said spokes, the inner and outer walls of the felly being connected by side walls and said outer wall comprising a centrally arranged tire supporting portion and tire supporting portions on each side of the first mentioned portion and connected to the side walls, respectively, there being braces or pillars extending 95 between the central portion and the side portions of such outer wall, and a circumferential rib extending between the central portion of the outer felly wall and connecting the same with the inner wall, the said side walls being provided with aligned 100 apertures and the said rib being provided with apertures coöperating with such apertures for the reception of bolts.

4. A wheel comprising a hub, spokes, and 115 a cast double-walled felly the inner wall whereof is connected to said spokes, the inner and outer walls of the felly being connected by side walls and said outer wall comprising a centrally arranged tire supporting portion, and tire supporting portions on each side of the first mentioned portion and connected to the side walls, respectively, there being braces or pillars extending 120 between the central portion and the side portions of such outer wall, and a circumferential rib extending between the central portion of the outer felly wall and connecting the same with the inner wall, the said side walls being provided with aligned 125 apertures and the said rib being provided with 130

- recesses extending inwardly from the central portion of the outer felly wall a sufficient distance to receive therewithin bolts inserted through the alined apertures in the 5 side walls.
5. A wheel comprising a hub, spokes, and a cast double-walled felly, the inner wall whereof is connected to said spokes, the inner and outer walls being connected by 10 side walls and the outer wall comprising a centrally arranged tire supporting portion, there being braces or pillars interposed between such central portion and the side walls, the outer surfaces of said pillars or 15 braces being depressed with reference to the central portion and the outer edges of said side walls.
6. A wheel comprising a hub, spokes, and a double-walled felly, the inner wall whereof 20 is connected to said spokes, the inner and outer walls being connected by radially extending walls, there being braces or pillars interposed between such radially extending walls, the outer surfaces of said pillars or 25 braces being depressed with reference to the tire-supporting portions of said walls.
7. A cast metal wheel comprising a hub, a tapered flange projecting therefrom, spokes formed with and extending from such flange, 30 said spokes being substantially U-shaped in section and having their flanges substantially flush with the enlarged end of the hub flange, a felly formed with the ends of the spokes and comprising an inner wall 35 and side walls, an outer wall connected to the side walls, and a circumferential rib connecting the inner and outer walls, said hub flange, spokes, and the walls and circumferential rib of the felly being of substantially the same thickness.
8. A wheel comprising a hub and a felly connected thereto, said felly having an outer supporting surface comprising a central circumferentially extending T-shaped rib and 45 a flange on each side of said rib and spaced therefrom and projecting toward the flange of said rib, the rib flanges and the lateral flanges forming jointly supporting surfaces for tire bases.
9. A wheel comprising a hub and felly connected thereto, said felly comprising an inner cylindrical wall, side walls extending radially from such inner wall, flanges projecting toward each other from said side 55 walls and overhanging the inner wall, and a support interposed between said flanges and forming with the outer surfaces of the flanges a tire supporting surface.
10. A cast metal wheel comprising a hub and a felly connected thereto, said felly comprising an inner cylindrical wall, lateral walls projecting from opposite sides of such inner wall and an outer wall connecting the ends of such lateral walls, the central portion 65 of the outer wall being supported by a rib extending between the same and the inner wall, the rib being recessed at intervals.
11. A cast metal wheel comprising a hub, a tapered flange projecting therefrom, 70 spokes formed with and extending from such flange, said spokes being substantially U-shaped in section and having their flanges substantially flush with the enlarged end of the hub flange, a felly formed with the ends 75 of the spokes and comprising an inner wall and side walls, an outer wall connected to the side walls, and a circumferential rib connecting the inner and outer walls, said hub flange, spokes, and the walls and circumferential rib of the felly being of substantially the same thickness.
12. A cast metal wheel comprising a hub and a felly connected thereto, said felly having an outer supporting surface comprising a central circumferentially extending T-shaped rib and a flange on each side of said rib and spaced therefrom, the rib and the said flanges forming jointly flat supporting surfaces for tire bases. 80
13. A wheel comprising a hub, spokes, and a cast double-walled felly the inner wall whereof is connected to said spokes, the inner and outer walls of the felly being connected by side walls and said outer wall 95 comprising a centrally arranged tire supporting portion, and tire supporting portions on each side of the first mentioned portion and connected to the side walls, respectively, there being braces or pillars extending between the central portion and the side portions of such outer wall. 100
14. A wheel comprising a hub, spokes, and a cast double-walled felly the inner wall whereof is connected to said spokes, the inner and outer walls of the felly being connected and said outer wall comprising a centrally arranged tire supporting portion and tire supporting portions on each side of the first mentioned portion, there being braces or pillars 105 extending between the central portion and the side portions of such outer wall. 110
15. A wheel comprising a hub, spokes, and a cast double-walled felly the inner wall 115 whereof is connected to said spokes and the outer wall whereof comprises a centrally arranged tire supporting portion, and tire supporting portions on each side of the first mentioned portion, there being braces or pillars 120 extending between the central portion and the side portions of such outer wall, and a circumferential rib extending between the central portion of the outer felly wall and the inner felly wall and connecting the outer 125 wall with the inner wall.
16. A wheel comprising a hub, spokes, and a cast double-walled felly, the inner wall whereof is connected to said spokes, the inner and outer walls being connected by side 130

walls and the outer wall comprising a centrally arranged tire supporting portion, and tire supporting portions on each side of the first mentioned portion and connected to the 5 side walls, respectively, there being braces or pillars extending between the central portion and the side portions of such outer wall, and a circumferential rib extending between the central portion of the outer felly wall and connecting the same with the inner wall.

10 17. A wheel comprising a hub, spokes, and a cast double-walled felly the inner wall whereof is connected to said spokes, the inner and outer walls of the felly being connected by side walls and said outer wall comprising a centrally arranged tire supporting portion, there being braces or pillars interposed between such centrally arranged portion and the side walls.

15 18. A wheel comprising a hub, spokes, and

a felly, said felly having outwardly projecting radially extending walls and a third substantially continuous outwardly projecting radially extending wall intermediate of the first mentioned walls, there being braces 25 or pillars interposed between each of the first mentioned walls and the intermediate wall and integrally connecting the same.

19. A wheel comprising a hub, spokes, and a felly having outwardly projecting radially 30 extending walls provided with flanges forming tire-supporting surfaces, a substantially continuous outwardly projecting radially extending wall interposed between said flanges, and braces or pillars interposed between said flanges and such intermediate wall.

In testimony whereof I hereunto affix my signature.

EDWIN H. JANES.
